UNITED STATES PATENT OFFICE.

JERROLD F. WALTON, OF STURGIS, MICHIGAN.

ADJUSTABLE CHAIR.

1,137,246.

Specification of Letters Patent. Patented Apr. 27, 1915.

Continuation of application Serial No. 486,470, filed March 29, 1909. This application filed January 29, 1912. Serial No. 674,024.

To all whom it may concern:

Be it known that I, JERROLD F. WALTON, a citizen of the United States, residing at Sturgis, Michigan, have invented certain new and useful Improvements in Adjustable Chairs, of which the following is a specification.

This invention relates to improvements in adjustable chairs, and this application is a continuation of my application for Patent Ser. No. 486,470, filed March 29, 1909.

The objects of this invention are: First, to provide a chair which is very effective in operation and which may be very conveniently knocked down and packed for shipment. Second, to provide an improved detachable depending arm from the chair back which may be readily disposed of in packing the chair and which shall be very strong and effective in use and be very simply assembled.

Further objects, and objects relating to details of construction and operation will definitely appear from the detailed description to follow.

I accomplish the objects of my invention by the devices and means described in the following specification. The invention is clearly defined and pointed out in the claims.

A structure constituting preferred embodiments of my invention is clearly illustrated in the accompanying drawing, forming a part of this specification, in which:

Figure I is a side elevation view of a chair embodying the details of my invention, certain portions being broken away and shown in section on a line corresponding to line 1—1 of Figs. II and IV. Fig. II is a rear elevation view of a chair embodying the features of my invention. Fig. III is a side elevation view of a chair embodying the features of my invention shown knocked down and packed ready for shipment. Fig. IV is an enlarged detail perspective view of the lower portion of the adjustable chair back and the downwardly depending detachable arm, portions being broken away to show details of construction. Fig. V is an enlarged detail perspective view of one of the pivot hinge members at the lower corner of the chair back. Fig. VI is a detail sectional view on line 6—6 of Fig. V, showing the details of construction, a portion of the engaging lug being shown in full lines. Fig.

VII is an enlarged detail perspective view of the pivot plate member of the hinge joint secured to the chair frame. Fig. VIII is an enlarged detail transverse sectional view on a line corresponding to line 8—8 of Fig. VI, showing the relations of the members 60 of the hinge joint of the chair back when assembled. Fig. IX is an enlarged detail sectional view on line 9—9 of Figs. I, II, IV and X, showing details of the means for supporting and retaining the detachable depending arm to the chair back. Fig. X is an enlarged detail sectional view on line 10—10 of Fig. IX. Fig. XI is an enlarged detail sectional view similar to the view of 10—10, showing the modification of the means of retaining the detachable depending arm to the chair back. Fig. XII is a sectional view on line 12—12 of Fig. XI.

In the drawing, all of the sectional views are taken looking in the direction of the little arrows at the ends of the section lines and similar numerals of reference refer to similar parts throughout the several views.

Referring to the lettered parts of the drawing, the chair is made up of a bottom frame 1 supported by suitable front posts 2 and rear posts 3, and carrying arms 4—4 provided with a cross bar 5 at the back of the chair bottom. A suitable cushion 6 is provided resting on spring structures 7 within the bottom frame. The adjustable back, made up of side bars 8 with bottom bar 9 and cross slats 9', is disposed between and suitably hinged to the back posts 3. The separate hinge at each side comprises the pivot pin 10 carried by the plate 11, which engages the hinge plate member 12 provided with a key hole opening, as will be hereafter described in detail.

A back cushion 13 is carried on the cushion support 14 formed of a metal rod, having hanger portions 15 at each end which are pivoted at 16 between the side bars 8 of the back. The lower portion 14 projects forwardly to form a ledge or shelf for the back cushion and supports the same above the bottom cushion 6.

A downwardly projecting back arm is constructed of a round straight bar 17 inserted in the holes 18 through the bottom cross bar 9 and the slats 9', 9', see particularly Figs. I, II and IV. This bar is an easy fit and is held up by transverse pin 19 engaging a plate 20 which is perforated to receive the arm. The plate 20 is slotted at 110

21 to permit the pin 19 to be inserted and turned into the engaging position, as clearly appears in Fig. IX. The plate 20 is disposed beneath the bottom bar 9 and is supported by suitable screw 22—22 in the under side of said bottom bar 9. The lower end of this bar 17 is slotted at 17' to connect with the link 23, which is pivoted to the slide 25 by pivot 25', which is carried on a bottom board 24. The link 23 is made detachable. It is preferably detachable from the bar 17, but serves its purpose if detached at the other end.

Modifications of structures for holding up the back arm or bar 17 appear in Figs. 11 and 12. The cotter pin 35 is shown inserted through the bottom cross bar 9 of the back through the perforation in the bar 17, which will support the same and prevent its rotation. The modification of the supporting plate is also shown, consisting of the L-shaped piece 36 secured to the bottom bar 9 by certain screws, the horizontal portion being disposed a little below the under side of the cross bar 9 and perforated for the bar 17 and notched at 37 to permit the pin 19 to pass and turn into engagement therewith.

The slide 25 is controlled by a clutch 26 which is operated by the push rod 26' provided with the push button 26" in any well known way. Preferably these parts are constructed according to the structure appearing in the patent application of myself and William Favorite, filed April 25th, 1910, Serial Number 557,479. These clutch parts are supported on the bottom board 24 running from front to rear of the chair, which is slotted at 24' to permit freedom of movement of the said downwardly depending arm 17. The back bar 5 is notched at 5' to accommodate the same. Springs 27 connect the front of the link 24 to the back part of the chair bottom and act to throw the back forward.

The hinge members are specially constructed, as will be seen by an inspection of Figs. IV, V, VI, VII and VIII. There is a hinge at each side of the back. The pivot plate 11 is provided with a projecting pivot pin 10, with T-head 30, and an oppositely projecting stud 28 engages the back side bars 8 in suitable holes 29 therein. A single screw 31 thus serves to retain this hinge member in place. A cross bolt 32 is disposed through the back side bar and prevents splitting thereof. The pivot plate 12 contains

the key-hole opening consisting of the round part 34 and the upwardly extending slot 33 therefrom. The general form of this plate is L-shaped, the horizontal part extending onto the back bottom bar 5 and the vertical part being offset to permit easy adjustment of the pivot 30 of the pivot member of the hinge. Screws 12' are disposed through the vertical part into the post 3, and a screw 12" is disposed through the horizontal part, thus firmly retaining the same and also strengthening the joint between these parts.

Having thus described my invention, what I claim as new and desire to secure by Letters Patent is:

1. In a knock-down chair structure, the combination of an adjustable back detachably connected to the body of the chair and made up of side pieces and cross pieces, a detachable arm with a round straight part disposed in an upright bore through said cross pieces, means for supporting said arm in said cross pieces, and detachable means connected to the lower end of said arm for adjusting the said back, all coacting as specified.

2. In a knock-down chair structure, the combination of an adjustable back detachably connected with the body of the chair and made up of side pieces and cross pieces, an arm with a straight part disposed in a bore in said cross pieces, means for supporting the said arm in said cross pieces, and detachable means connected with the lower end of said arm for adjusting the said back, all coacting as specified.

3. In a knock-down chair structure, the combination of an adjustable detachable back, with a separable hinge joint for securing the same to the body of the chair, a detachable arm disposed in an upright bore in said back, means for supporting the same detachably in position comprising a laterally projecting pin on the said arm and a plate on said back positioned to engage the said pin when the arm is turned to normal position, and detachable means connected to said arm for adjusting the angle of said back, coacting as specified.

In witness whereof, I have hereunto set my hand and seal in the presence of two witnesses.

JERROLD F. WALTON. [L. S.]
